By Attorney George H. Christy

UNITED STATES PATENT OFFICE.

MAX LIVINGSTON, OF PITTSBURG, PENNSYLVANIA.

OIL-STILL.

SPECIFICATION forming part of Letters Patent No. 237,560, dated February 8, 1881.

Application filed July 17, 1880. (No model.)

To all whom it may concern:

Be it known that I, MAX LIVINGSTON, of Pittsburgh, county of Allegheny, State of Pennsylvania, have invented or discovered a new and useful Improvement in Oil-Stills; and I do hereby declare the following to be a full, clear, concise, and exact description thereof, reference being had to the accompanying drawings, making a part of this specification, in 10 which—like letters indicating like parts—

Figure 1 illustrates, by a sectional elevation, part of an oil-still with my improvement applied thereto. Fig. 2 shows an end elevation of the same; and Figs. 3 and 4 illustrate, by 15 views in elevation and top plan, respectively, my improvement as applied to a vertical still of the class known as the "Gracie still."

In the distillation of petroleum the vapors driven off from the oil in the still have a considerable range of variation in specific gravity, from the lighter benzines to the heavy paraffine oils. Several forms of stills have been employed for effecting such distillation. Those most commonly in use are provided with one 20 or more vapor-outlets or goose-necks, which lead off from the still-chamber at a common height above the oil to be distilled. As thus arranged the heavy and light vapors must rise to the same height to find escape; but in so 25 doing the heavy vapors are more or less retarded, owing to their greater gravity, and, becoming highly heated by their protracted retention in the still, they are more or less decomposed, or "cracked," as it is technically 30 termed, into tarry residuum and "light ends," which have an offensive odor and injure the quality of the distillates. Also, stills have 35 been known and described having a number of vapor-outlets all opening from the side of the still, below the top or dome, at different 40 points in the height of the still. In these, as well as in the stills first mentioned, the vapors of different gravity fill the still-chamber, and paraffine-vapors become intermingled and 45 pass off through the upper openings along with the vapors of the illuminating-oil. In order to separate the paraffine-oils so as to render the illuminating-oil fit for use, an expensive process or treatment has been resorted 50 to, and to obtain the heavier distillates redistillation by steaming and other methods of re-

fining have been practiced. In the progress of the arts these heavy distillates have become very valuable, especially when obtained pure and free from light oils of offensive odor and 55 low fire-test.

My invention is designed to secure these various grades of distillates of the desired quality and purity at one distillation in a single still. This I do by providing a goose-neck 60 or vapor-escape passage, leading upward from the top of the still-chamber, through which the lightest vapors, including that of illuminating-oil, pass from the still, and in addition thereto I provide, in the side or sides of the 65 still-chamber, a plurality or succession of vapor-outlets, arranged in different horizontal planes or at different points in the height of the still, which side passages are controlled by valves, whereby any or all such passages 70 above the level of oil in the still may be opened, and the vapors of different degrees of gravity will, owing to their natural tendency to separate, find their appropriate outlets. The lighter vapors, including the illuminating-oils, 75 rise above the still-chamber in the goose-neck and escape through the same, while the paraffine and other heavy vapors, not readily rising to such height, find more ready escape through the side openings, the lighter paraffine vapors taking the upper side openings 80 and the heavy vapors taking the lower side openings, and all escaping from the still with equal or nearly equal freedom.

I have represented in the drawings two 85 forms of stills—in Figs. 1 and 2 the ordinary boiler-shaped or cylindrical still, and in Figs. 3 and 4 a vertical still made circular and having radially arranged heating-furnaces, and known as the "Gracie still." These two forms 90 I have shown simply for illustration, my invention being equally applicable to both, as well as to stills of other forms or patterns.

As here shown, A represents the still; B, Fig. 1, the oil in the still, and D the furnace 95 for heating the oil. These parts may be of the usual or any desired construction. In the top or dome of such a still I provide a goose-neck or vapor-passage, C, which extends upward above the still-chamber and thence leads off 100 to any suitable condensing apparatus. In operation, this vapor-passage C is, by preference,

kept open from the beginning to the end of the "run" or distillation, and it is designed to carry off the lightest of the distillates, including the illuminating oils. But in order to carry off the heavier vapors I provide a series or succession of vapor-pipes, $a' a^2 a^3 a^4 a^5$, &c., in any desired number, leading off from the side or end of the still at different levels, or from different points in the height of the still, to one, two, or more drums or separators, E E', which latter are arranged in convenient proximity to the still and receive and treat the vapors as presently described. In these several vapor-pipes I arrange cocks or valves $b b'$ $b^2 b^3 b^4 b^5$, &c., so that any or all the pipes or passages may be opened and closed at pleasure.

When charging the still all the side pipes are closed, and then, as the distillation progresses and the quantity of oil in the still is reduced, one after another of these pipes, as the oil falls below them, is opened, thus providing at all times vapor-escape passages near the surface of the oil R. By means of such low passages the heavy vapors are enabled to pass off readily without being compelled to rise high in the still, and thereby superheating and consequent cracking are avoided. They are, therefore, free from "light ends" and the offensive odor due to the same. While the vapors within the still-chamber do have a tendency to separate by gravity, as stated, yet it is true that if only side openings from such chamber are provided a considerable quantity of paraffine-vapors will pass off with the illuminating-oils from the upper side openings, owing to the fact that such vapors are carried together, by a common force, toward the top of the still, and such heavy vapors as may thus be carried upward will pass from a side opening as readily as light vapors, and in a still having side openings only, the purposes of my invention will not be fully secured; but by providing the open passage C, which is much smaller than the still-chamber, and rises above its top or dome, I aid the natural tendency to separation by gravity, by the mechanical structure of the still; or, in other words, the illuminating-oil and lighter vapors rise in this passage C, filling the same, while the heavier or paraffine vapors are thereby kept back within the larger body of the still-chamber, from which they have more ready escape by means of or through the side passages. By means of this freedom from cracking and separation by gravity in the still I not only obtain illuminating-oils free from paraffine, but also different grades of heavier distillates which are practically pure, of uniform consistency for each separate grade, free from offensive odors, and of high fire-test, adapted for lubricating and other purposes, and this is done at one distillation and in one still.

By means of gage-cocks c' to c^5 , &c., the height of oil in the still can be determined at any time, and the several vapor-pipes $a' a^2$, &c., be opened accordingly. In order to produce

drainage in these pipes toward the still so that any free oil or condensed vapors in the pipes may return to the still, I reduce the size of these pipes from the still toward the valves, thereby giving the bottoms of the pipes a downward slope or inclination into the still, as at i, Fig. 1. These pipes $a' a^2$, &c., may be secured to the still and to their respective drums E E' in any convenient way. I have shown two of these drums or separators—one, E, receiving the pipes $a' a^2$, and the other, E', the pipes $a^3 a^4 a^5$. Any desired number of these drums may be used, however, the number depending upon the number of different grades of heavy distillates desired, as by using such number the separation of the vapors by gravity in the still is preserved, while by them a further or more complete separation is effected or promoted. Occasion is given for the use of such separators from the fact that a small percentage of light vapors will likely escape with the heavy vapors through the side openings, and also from the practical difficulty of obtaining perfect separation by gravity through side openings only, as before stated.

The drums are constructed and operated in the usual way. A steam-coil, e, enters at the top and passes to the bottom of the drum, where the steam, which becomes highly heated by its passage through the hot vapors, escapes through jet-holes e' into the body of the free and condensed vapors, producing agitation therein, and a separation of any light vapors that may be present, which latter rise and escape through pipe e^2 at the top of the drum, while the heavy vapors or oil escape through pipe e^3 at the bottom of the drum. These pipes e^2 and e^3 lead to separate condensers, in which the vapors are treated in the usual way. If preferred, a drum or separator may be used for each of the vapor-pipes of the still; but for ordinary commercial purposes one drum will suffice for two or three vapor-pipes when arranged as I have shown them.

In Fig. 1 I have shown my improvement applied to both ends of the still, and in Figs. 3 and 4 at four different points in the circumference of the still there shown. By this means the distance which the vapors in the still must move to find escape is reduced. This not only reduces the pressure in the still, but also tends to equalize the existing pressure in all its parts, and to this extent facilitates the vaporization of the oil in the distilling operation.

I claim herein as my invention—

1. An oil-still having a vapor-escape passage, C, opening into and extending above the top of the still-chamber, in combination with a succession of valve-governed vapor-escape passages, $a' a^2$, &c., leading off from the side of the still-chamber at different points in its height, substantially as and for the purposes set forth.

2. An oil-still having a vapor-escape passage, C, opening into and extending above the

still-chamber, with a succession of valve-governed vapor-escape passages, *a a'*, &c., leading off from the side of the still-chamber at different points in its height, in combination 5 with two or more separators, *E E'*, arranged as described, to receive and separate the vapors escaping through the side passages, substantially as set forth.

In testimony whereof I have hereunto set my hand.

MAX LIVINGSTON.
